UNITED STATES PATENT OFFICE.

JOSEPH TOPLITZ, OF NEW YORK, N. Y.

FABRIC-HOLDING APPARATUS FOR EMBROIDERING-MACHINES.

1,175,667.

Specification of Letters Patent. Patented Mar. 14, 1916.

Application filed August 25, 1913. Serial No. 786,392.

To all whom it may concern:

Be it known that I, JOSEPH TOPLITZ, a citizen of the United States, residing at New York city, in the county of New York and State of New York, have invented certain new and useful Improvements in Fabric-Holding Apparatus for Embroidering-Machines, fully described and represented in the following specification and the accompanying drawings, forming a part of the same.

This invention relates to fabric holding apparatus for embroidering machines, and the invention has been made with the idea of providing apparatus of this kind which shall be adapted for holding, suitably stretched, a large number of separate pieces of fabric to be operated upon at the same time in the machine.

The invention is especially applicable to, or adapted for use in connection with, embroidery machines of the kind generally known as Swiss embroidering machines, in which the fabric to be embroidered is carried by a frame which is mounted to vibrate or move in a suitable manner according to the pattern to be embroidered in suitable relation to the embroidering needles; and the invention aims to provide apparatus for attachment to such a machine when it is desired to embroider on a number of separate pieces of cloth, as for example, a large number of small handkerchiefs or similar pieces of fabric, which apparatus shall be of such a character that it may readily be attached to the vibrating frame or fabric carrying member of the machine, without necessitating any substantial change in the vibrating frame or in other coöperating parts of the machine which would result in loss in time or labor or render the machine unadapted for other classes of work.

The invention also aims to provide fabric holding devices of such a character that the separate pieces of fabric may be readily and quickly stretched on the holding devices and securely held in position without damage, and that the unstretched portions of the fabric may be readily disposed and held out of the way while the fabric is in the machine.

With these ends in view the invention consists in various features of construction, arrangement and combinations of parts as hereinafter fully described and particularly pointed out in the claims.

A full understanding of the invention can

best be given by detailed description of an approved construction embodying the various features of the invention, and such a description will now be given in connection with the accompanying drawings, in which—

Figure 1 is a broken perspective view of so much of an embroidering machine provided with apparatus embodying my invention as is necessary for illustrating and giving an understanding of the same. Fig. 2 is a sectional view of the assembling or carrying frame shown in Fig. 1, taken on line 2 of Fig. 1. Fig. 3 is a front view on a smaller scale of a portion of the assembling frame with a number of the fabric holding frames in position therein, the fabric holding frames being shown without any fabric stretched thereon and with the retaining rods removed for clearness. Fig. 4 is a perspective view on a large scale of one of the fabric holding frames. Fig. 5 is a longitudinal sectional view of a fabric holding frame taken on line 5 of Fig. 4. Fig. 6 is a cross-sectional view on a still further enlarged scale showing two adjacent fabric holding frames as they stand when assembled in the assembling frame and with handkerchiefs or other pieces of fabric stretched thereon. This view shows the frames of full size as they have been made.

Referring to the drawings, parts 10, 11 and 12 in Fig. 1 represent respectively the lower horizontal beam, one of the end uprights and an intermediate upright of a vibrating frame of an embroidering machine. Mounted on these parts of the vibrating frame are two relatively adjustable supporting bars or members 13 and 14 for supporting and holding in position a carrying or assembling frame 15, and these supporting members are formed in the construction shown by oppositely facing channel bars or beams, the lower channel bar 13 being supported as shown in Fig. 1 on an I beam 10 of the vibrating frame, as by means of brackets 16, and the upper channel bar 14 being carried by a horizontal bar or beam 17 which is mounted on the upright members 11 and 12 of the vibrating frame in such a way as to be movable or adjustable vertically to permit the assembling frame to be placed in position between and removed from the supporting bars 13 and 14. As shown, the beam 17 is carried at one end by a bracket 18 which has a slot and bolt con-

connection with the upright 11, and at the other end the beam 17 is carried by a bracket 19 which has a split collar adapted to slide on the upright or rod 12 and to be secured thereto by means of the bolt or screw 20. The beam 17 and channel bar 14 are shown in Fig. 1 of the drawings in raised position to permit the placing or removal of the assembling frame. By moving the beam 17 downward from this raised position, the channel bar 14 may be brought down to position to receive the upper bar of the frame 15, and being then secured in such lowered position, the assembling frame will be securely positioned and held in place in the vibrating frame of the machine. The vibrating work carrying frame of embroidery machines of the kind to which the present invention is especially applicable are commonly made of such large size as to afford space for mounting therein several assembling frames of such size as are employed in embroidering handkerchiefs, for example, and such frames may be arranged in the vibrating frame in two or more rows or tiers, one above the other, with two or more assembling frames in each row according to the length of the assembling frames. I have for convenience made the assembling frames approximately 2½ yards long and 1 foot high.

The pieces of fabric to be embroidered are stretched on holding devices carried by the assembling frame 15 and which in the construction shown are provided by removable fabric holding frames 25 adapted to be assembled and held side by side in the assembling frame. These fabric holding frames will be of size suitable according to the character of the work to be done and are conveniently made of rectangular shape with their vertical dimension as they stand in the machine considerably greater than their dimension horizontally or lengthwise of the assembling frame. The two side bars of each holding frame are formed with longitudinally extending fabric holding channels 26 opening toward one face, which may be called the front, of the frame, and into which channels the fabric may be pressed and held by means of removable retaining rods 27. These rods are of a size to fit snugly in the channels with the fabric passed about them and are best formed as shown of metal rods provided with a tubular casing or covering of india rubber or other suitable yielding material, although a suitable yielding surface rod might of course be made in other ways. The outer sides of the side bars, or side edges of the frame, are formed with outwardly extending rear flanges 28 so that when the frames are placed in adjoining positions, as when assembled in the assembling frame and as shown by Fig. 6, the flanges 28 of adjacent frames will abut and position the frames

relative to each other so as to leave a longitudinally extending recess or channel between each frame and its next adjoining frame, as shown at 29 in Fig. 6, into which the extending unstretched portions of the pieces of fabric stretched on the frames may be tucked and held out of the way. In order that the fabric thus tucked into the recesses 29 between adjoining frames shall be more securely held in place, the side edges of the frames are formed also with front projecting flanges 30 to provide the recesses with undercut side walls, the flanges 30 being shorter, however, than the rear projecting flanges 28 so as to leave sufficient open space for the tucking in of the unstretched portions of the fabric. The end bars of the frames 25 are also best formed with front opening fabric receiving channels so that the fabric may, if desired, be held at the ends as well as the sides of the frame, and instead of providing independent retaining rods for these channels 25^a, the retaining rods 27 may each be formed with an angularly extending portion 27^a to fit in one of the channels 25^a. Usually, however, it is most desirable to secure the fabric merely in the side channels 25, and in such case, instead of entirely removing the retaining rods from the frame in applying and removing the fabric, they may, when of the angular form shown, be lifted from the side channels 25 by being allowed to pivot in the end channels 25^a. The portions of the frame which form the outer walls of the channels 25 and 25^a are best cut away or terminated at the corners so as to provide open ended channels, and the retaining rods may in such case be provided with lifting extensions 31, whereby the end of the rod may be conveniently raised from the channel. In order that the frames 25 shall be of light weight and yet strong, compact and cheap to make, they are best made by casting in a single piece from aluminum or a suitable aluminum alloy.

The assembling frame is of rectangular shape of a width or height corresponding to the length of the fabric holding frames 25 and of such length as desired to hold the desired number of holding frames placed side by side therein, and the side bars of the frame are formed with channels to receive the ends of the fabric holding frames. Both the ends and sides of the frame are best made of metal channel bars as shown secured together with the channeled sides or faces of the bars facing inwardly, and one end bar, as the bar 35 at the right hand end in Fig. 1, is removably secured, as by means of screws extending through the flange portions of the side bars and through blocks 36 extending beyond the cut-away flange portions of the end bar as clearly shown in Fig. 2. By removing the screws the end bar 35 is left free

to be removed and the fabric holding frames may then be slid into position in the assembling frame or removed therefrom. The fabric holding frames when in position in the assembling frame abut against each other and fill the whole space within the assembling frame or as much thereof as may be desired. After the holding frames have been placed in the assembling frame the end 10 bar 35 is replaced and secured in position.

It is desirable that the assembling frame with its contained fabric holding frames shall not be at any part of such thickness as to interfere with the operation of the embroidery mechanism of the machine or as to necessitate change or modification of such mechanism as made for work of other character. My work holding frames and assembling frames are therefore made with the 15 idea of avoiding any such undesirable thickness in any part thereof, and with this idea in mind, I make the bars of the assembling frame of a thickness substantially the same as that of the work holding frames and 20 form the ends of the work holding frames with reduced portions 37 to fit within the channels in the side bars of the assembling frame. It will be noticed that the assembling frame is of rather light construction 25 for its length, but this is not objectionable, since when the frame is in working position in the machine, the long side bars of the assembling frame are supported by the channeled supporting bars 13 and 14, which 30 receive the side bars of the assembling frame and thus efficiently reinforce the same. The front flanges of the end bars of the assembling frame are best cut away slightly as shown at 38 in order to provide 35 sufficient space between them and the flanges 30 of the end holding frames for convenient tucking in of extending portions 40 of material stretched on such frames.

In using the apparatus above described, 45 the fabric holding frames may have the material to be embroidered stretched thereon before the frames are assembled in the frame 15, but usually the desired number of holding frames will be assembled in the 50 assembling frames and will then remain in position and have handkerchiefs or other pieces of fabric stretched thereon and removed therefrom as desired until such time as it may be desirable or necessary for any 55 reason to remove the holding frames from the assembling frames, as because of breakage or injury to some holding frame or for substituting frames of different size or other reason. When pieces of fabric to be 60 embroidered are to be stretched, an assembling frame with its contained holding frames is conveniently laid flat on a table or other suitable support and the pieces of fabric 65 separately secured to the different holding frames by stretching the portion of each

piece to be embroidered over the face of the frame to which it is to be secured while the retaining bars 27 are wholly removed from the frame or lifted out of the channels 25 while their short arms 27^a remain in the end 70 channels 25^a; then the bars are pressed down to force the material into the channels and to stretch the material across the frame and hold it securely in its stretched condition, as shown in Fig. 6. The extending portions 75 of the material may then be rolled up and tucked into the adjacent recesses 29 or otherwise tucked into the recesses as indicated also in Fig. 6. When the pieces of fabric to be embroidered have all been 80 stretched on the holding frames, the assembling frame with its contained holding frames is positioned on the vibrating frame of the embroidering machine by placing the lower side of the assembling frame in the 85 channel of the supporting bar 13 and then with the frame in position lowering the upper supporting bar 14 and securing it in its holding position.

The object of having the fabric holding 90 frames or devices formed as separate frames and removably mounted in the assembling frame 15 is merely one of convenience for permitting removal of broken or injured frames or substituting frames of different 95 sizes. Obviously, it is not necessary for all purposes of the invention that such separate and removable holding devices shall be used, and the construction might be made otherwise to provide the carrying or assembling frame with fabric holding channels 100 25 arranged in pairs with an unobstructed space between the channels of each pair across which the pieces of fabric may be stretched and with recesses between each 105 pair of channels for receiving the unstretched portions of the pieces of fabric; and the means for providing such pairs of 110 fabric holding channels instead of being carried by a removable carrying frame 115 might be otherwise secured to the vibrating frame of the embroidering machine as desired. It is to be understood, therefore, that the invention is not to be limited 115 whether in the above particulars or in other ways to the exact construction, arrangement or combinations of parts as shown in the drawings and to which the foregoing description has been mainly confined, but that it includes changes and modifications there- 120 of within the claims.

What is claimed is:—

1. Fabric holding apparatus for embroidering machines comprising means formed to provide holding channels arranged in pairs 125 with the channels of each pair spaced for the stretching of fabric between them and to provide fabric retaining recesses between adjacent channels of adjacent pairs to receive unstretched portions of the fabric, 130

the sides of the recesses being adapted to frictionally engage and hold the fabric, and retaining devices for pressing the fabric into said channels.

5. 2. Fabric holding apparatus for embroidery machines comprising fabric holding devices arranged to provide a plurality of unobstructed spaces across which pieces of fabric may be stretched, said devices being 10 formed with fabric holding channels and to provide fabric retaining recesses between side walls of adjacent fabric holding channels to receive and hold unstretched portions of the fabric.
- 15 3. Fabric holding apparatus for embroidery machines, comprising a plurality of fabric holding devices each having channeled side members formed with fabric holding channels and arranged to provide 20 an unobstructed space across which a piece of fabric may be stretched, said holding devices being formed to provide a fabric retaining recess with undercut side walls between channeled side members of adjacent 25 holding devices for receiving the unstretched portions of the fabric.

4. Fabric holding apparatus for embroidery machines comprising in combination with a vibrating frame, a carrying frame 30 movably mounted in the vibrating frame and provided with fabric holding devices including members extending across the carrying frame and arranged to provide a plurality of unobstructed spaces across which 35 the fabric may be stretched and formed to provide fabric retaining recesses with undercut side walls between adjacent stretching spaces for receiving the unstretched portions of the fabric, and parts to coöperate with 40 said members to stretch and hold the fabric.

5. Fabric holding apparatus for embroidery machines, comprising in combination with a vibrating frame, a carrying frame 45 movably mounted in the vibrating frame, and a plurality of fabric holding frames 50 movably mounted in the carrying frame, said fabric holding frames having means for stretching and securing the fabric thereon whereby the fabric may be stretched thereon and removed therefrom while the holding frames are mounted in the carrying frame, and said fabric holding frames being formed to provide fabric retaining recesses 55 between adjacent frames to receive unstretched portions of the fabric, the sides of the recesses being adapted to frictionally engage and hold the fabric.

6. Fabric holding apparatus for embroidery machines, comprising in combination 60 with a vibrating frame, a pair of horizontally extending and relatively adjustable

channeled supporting members, a carrying frame removably mounted in said supporting members, said carrying frame having parallel side members formed by channel 65 bars set with their channels opening inwardly and of a size to fit into the channels of said supporting members, and a plurality of fabric holding frames mounted in said carrying frame, said holding frames 70 having their ends formed to fit within the channels of the side members of the carrying frame.

7. Fabric holding apparatus for embroidery machines, comprising a carrying frame 75 having parallel channeled side bars set with their channels opening inward, and a plurality of fabric holding frames removably mounted in said channeled side bars of the carrying frame, the side bars of the fabric 80 holding frames which extend transversely of the carrying frame being formed with fabric holding channels opening toward the front of the frames and being formed to provide recesses between the side bars of adjacent fabric holding frames in which unstretched portions of the fabric stretched on the frames may be tucked, the sides of the recesses being adapted to frictionally engage 85 and hold the fabric.

8. A fabric holding frame for embroidery machines, comprising side bars formed with fabric holding channels opening toward the front of the frame, and retaining rods fitting in said channels to hold the fabric stretched between said side bars, the side edges of the frame being shaped to provide a recess between the frame and an adjoining frame opening toward the front of the frame and closed at the back and in which the extending portion of a piece of fabric stretched on the frame may be tucked.

9. A fabric holding frame for embroidery machines, comprising side bars formed with fabric holding channels opening toward the front of the frame, and retaining rods fitting in said channels to hold the fabric stretched between said side bars, the side bars having rear spacing flanges for engaging similar flanges on adjoining frames 105 when a plurality of frames are assembled, whereby recesses are provided between adjoining assembled frames in which unstretched portions of fabric stretched on the frames may be tucked.

In testimony whereof I have hereunto set my hand in the presence of two subscribing witnesses.

JOSEPH TOPLITZ.
